LEO RAPP, OF PITTSBURGH, PENNSYLVANIA, ASSIGNOR TO WESTINGHOUSE ELECTRIC
AND MANUFACTURING COMPANY, A CORPORATION OF PENNSYLVANIA.

COIL-SUPPORT.

1,119,988.

Specification of Letters Patent.

Patented Dec. 8, 1914.

Application filed October 23, 1912. Serial No. 727,290.

To all whom it may concern:

Be it known that I, LEO RAPP, a citizen of the United States, and a resident of Pittsburgh, in the county of Allegheny and State of Pennsylvania, have invented a new and useful Improvement in Coil-Supports, of which the following is a specification.

My invention relates to dynamo-electric machines, and it has special reference to field coil supporting structures for machines having polar projections which are provided with series or commutating field coils concentrically disposed around main shunt field coils.

One of the objects of my invention is to provide a simple and effective device of the above-indicated character which may be cheaply and readily made from sheet metal, or the like, and which shall be light and durable in construction.

Another object of my invention is to provide a supporting structure for concentrically disposed field coils which shall embody resilient means for independently maintaining each of the coils firmly in position, so that chattering and vibration, such as is commonly encountered, is prevented.

Another object of my invention is to provide a supporting structure that may be assembled with facility and that shall, by reason of its peculiar construction, be adapted to support field coils which not only may have slight variations in width due to non-uniformity in the manufacture, but will also accommodate coils of various sizes, so that a single size of supporting bracket may be utilized for a number of different sizes of machines.

A still further object of my invention is to provide means for maintaining the shunt coil against the pole tips of the polar projection and also for supporting the series coil in concentric relation therewith, in such manner as to permit liberal heat radiation and ventilation.

In Patent No. 1,086,096, granted to Charles W. Starker on Feb. 3, 1914, on a co-pending application and assigned to the Westinghouse Electric & Mfg. Company, a dynamo-electric machine is disclosed having coil-supporting brackets of the same general class as that to be hereinafter described, but the coil-supporting structure set forth in the application referred to, is not provided with means for resiliently

maintaining the series coil in position, and, furthermore, it is not adapted, by reason of any yielding means or otherwise, to accommodate itself to variations in the widths of the series coils.

60

When supporting brackets of the above mentioned type are employed commercially for all machines of a particular design or class, a large number of sizes of brackets are necessary for different sizes of machines, which involves unnecessary expense, and, moreover, such coil supports make it necessary that the series coils be of exact dimensions.

65

According to my present invention, I propose to provide a coil-supporting structure that shall be so constructed as to overcome the objections hereinbefore recited and that may be employed either in connection with compound wound dynamo-electric machines or shunt wound machines having commutating coils disposed upon the polar projections in concentric relation with the main shunt field coils.

70

According to my present invention, I propose to provide a coil-supporting structure that shall be so constructed as to overcome the objections hereinbefore recited and that may be employed either in connection with compound wound dynamo-electric machines or shunt wound machines having commutating coils disposed upon the polar projections in concentric relation with the main shunt field coils.

75

My invention is illustrated in the accompanying drawing in which—

80

Figure 1 is a view, partially in side elevation and partially in section, of a portion of a dynamo-electric machine embodying my invention. Fig. 2 is a face view, taken in the direction of the arrow shown in Fig. 1, of a portion of the polar projection and its associated field coils, said parts being detached from the field magnet frame for the sake of clearness. Fig. 3 is a sectional view, taken along the line III—III of Fig. 1, showing the relative arrangement of the field coils and the supporting structure therefor. Fig. 4 is a perspective view of a field coil support, such as is shown in Fig. 1, and Fig. 5 is also a perspective view of a modified form of supporting structure embodying my invention.

85

Figure 1 is a view, partially in side elevation and partially in section, of a portion of a dynamo-electric machine embodying my invention. Fig. 2 is a face view, taken in the direction of the arrow shown in Fig. 1, of a portion of the polar projection and its associated field coils, said parts being detached from the field magnet frame for the sake of clearness. Fig. 3 is a sectional view, taken along the line III—III of Fig. 1, showing the relative arrangement of the field coils and the supporting structure therefor. Fig. 4 is a perspective view of a field coil support, such as is shown in Fig. 1, and Fig. 5 is also a perspective view of a modified form of supporting structure embodying my invention.

90

Referring to the drawing, the device here shown comprises a field magnet frame or yoke 1 having a plurality of polar projections 2, each of which is provided with a shunt field coil 3 and a series or commutating field coil 4, said coils being concentrically disposed and maintained and supported in position by means of a plurality of coil-supporting members or brackets 5. The field magnet frame 1 and the polar projections 2 may be of any well known construction, and the polar projections 2 are preferably detach-

95

100

105

110

ably mounted upon the field magnet frame 1 by suitable bolts 6. The shunt coil 3 comprises a plurality of convolutions of insulated conductor which are bound together 5 to form a single unit, in accordance with well known practice. The shunt coil 3 is long and relatively thin and fits comparatively tightly around the polar projection 2, the inner end thereof resting against pole 10 tips 8 of said polar projection. The series or commutating coil 4 may also be of any construction that is common in the art, said coil being short, as compared with the shunt coil 3, and of such dimensions that it is 15 adapted to surround the shunt coil 3 and be liberally spaced therefrom in order to insure good ventilation and radiation. The series coil 4 is conveniently located substantially midway between the ends of the shunt coil 20 3, although I do not wish to be restricted to this particular arrangement, as it may be desirable to locate the same either near the inner end of the shunt coil 3 or near the opposite end adjacent to the field magnet 25 frame 1.

In order to support the outer coil 4 in position and also to maintain the shunt coil 3 firmly against the pole tips 8 so that chattering and vibration thereof shall be prevented, a plurality of supporting brackets 5 are employed, which are severally disposed on the opposite sides of each of the shunt coils 3, in a manner to be hereinafter set forth. The supporting bracket 5 comprises 35 a plurality of arms 9 and 10, and a yoke or connecting member 11. The free ends of the arms 9 and 10 are provided with outwardly disposed projecting flanges 12 for coöperative engagement with the outer or series coil 4, while the yoke member 11 is provided with a plurality of inwardly projecting fingers 13 which are spaced apart in such manner as to provide a plurality of slots or 40 openings 14 for the reception of a spring or resilient member 15. The inwardly projecting fingers 13 are adapted to coöperate with the outer end of the shunt coil 3, and the arms 9 and 10 and yoke 11 are adapted to rest 45 flatly against the side of the shunt coil 3.

The spring 15 is preferably of V-shape and may conveniently be constructed of leaf or strap material which is fashioned into substantially the form indicated, the mid portion thereof being disposed between 50 the middle finger 13 and the outer end of the shunt coil 3, while the opposite end portions project through the several openings 14 and rest against the inside of the field magnet frame 1. By reason of the resiliency of the spring member 15, the shunt coil 3 is held 55 away from the frame 1 and is pressed firmly against the pole tips 8. The yoke portion 11 is also provided with a plurality of outwardly projecting fingers 16 that are adapted to support a V-shaped spring 17 of sub-

stantially the same type as that already described. A wearing plate 18 is provided with a tongue portion or apron 19 that is disposed substantially at right angles thereto, and said apron 19 is located intermediate 70 the supporting arms 9 and 10 and between the shunt coil 3 and the outer series coil 4. The wearing plate 18 rests against the outer end of the coil 4 and is engaged by the ends of the spring 17, thereby relieving the coil 75 4 from unnecessary wear due to the pressure exerted by the ends of the spring 17.

Preferably, the supporting brackets 5 are formed of sheet metal punchings, but other forms of supporting devices may be employed without departing from the spirit and scope of my invention.

It is evident, from the construction already set forth, that it is unnecessary to make the field coils of exact dimensions, inasmuch as the resiliency of the members 15 and 17 permits of considerable variation in size. Moreover, it will be found in commercial practice that coil support 5 of a single size may be employed to support coils of 80 widely different design and dimensions by reason of the element of yielding that is afforded by the springs 15 and 17.

Reference may now be had to Fig. 5 which illustrates a field coil support of a somewhat similar construction to that just described, except that, in place of the plurality of fingers 16, a single flange 16^a is provided which is adapted to coöperate with the spring 17 that is disposed between said 95 flange 16^a and the wearing member 18. The wearing member 18 is provided with a projecting edge or rim 20 in order to prevent the spring 17 from being displaced. Obviously, under certain conditions, it may be 100 found desirable to omit the wearing plate 18 and to permit the opposite ends of the spring 17 to bear directly upon the outer coil 4. These and other modifications in the structural details and arrangement and location of parts may be effected without involving the exercise of the invention, and I desire that only such limitations shall be imposed as are indicated in the appended 110 claims.

I claim as my invention:

1. In a dynamo-electric machine, the combination with a field magnet frame having a plurality of polar projections, and a plurality of field coils concentrically disposed thereon, of unitary structures disposed on the opposite sides of said coils for independently and resiliently maintaining and supporting said coils in position.

2. In a dynamo-electric machine, the combination with a field magnet frame having a plurality of polar projections, and a plurality of field coils concentrically disposed thereon, of means comprising resilient devices for maintaining one of said coils in 125 130

position, and resilient devices associated with said means for supporting the other coil in position.

3. In a dynamo-electric machine, the combination with a field magnet frame having a plurality of polar projections, and a plurality of field coils concentrically disposed thereon, of a plurality of supporting brackets associated with one of said coils and disposed on the opposite sides thereof, resilient means disposed between said brackets and said magnet frame for exerting a separating pressure between said coil and said frame, and resilient means associated with said brackets for coöperating with the other field coil and securing it in position.

4. In a dynamo-electric machine, the combination with a field magnet frame having a plurality of polar projections, and a plurality of field coils concentrically disposed thereon, of a plurality of supporting grids or brackets severally disposed on the opposite sides of one of said coils, a spring mechanically associated with a portion of each supporting grid or bracket and adapted to press against the field magnet frame, means associated with said grids or brackets for

engaging the other field coil, and other means associated therewith and embodying a spring for forcing said second field coil 30 against said coil-engaging means.

5. In a dynamo-electric machine, the combination with a field magnet frame having a plurality of polar projections, and a plurality of field coils concentrically disposed 35 thereon, of grids adapted to engage the ends of one of said coils, springs interlocked with said grids and serving to exert a separating pressure between the same and said frame, coil-engaging flanges associated with said 40 grids, an independent wearing member adapted to rest against the outer coil, and a spring interlocked with said grid and engaging said wearing member for forcing said second coil against the coil-engaging 45 flanges.

In testimony whereof, I have hereunto subscribed my name this 12th day of Oct., 1912.

LEO RAPP.
